9 Claims. (Cl. 33—86)

The present invention relates to an arrangement for aligning track rails, and more particularly to the correction of track curves. It is designed to carry out the track aligning method disclosed and claimed in our copending application Serial No. 32,904, filed May 31, 1960.

In our prior application, there is disclosed a method of aligning a track point with a desired track section extending between two end points. This method proceeds from a first portion of the track section, which has previously been aligned, and the track point to be aligned lies outside an imaginary succeeding portion of the track section. It comprises the steps of laying a first chordal element between the end points of the track section, laying a second and shorter chordal element between a point of the first track section portion and the track point to be aligned, measuring a first parameter defining a point of the first track section portion in relation to the first chordal element, transforming this parameter into an analogous parameter for the shorter chordal element and moving the track point until the shorter chordal element has this analogous parameter. In particular, the measured parameter is the ordinate or offset of the first chordal element and its value is transformed into the value of the ordinate of the shorter chordal element.

Accordingly, in the arrangement of the present invention, two chordal reference elements of unequal length are associated with one, preferably each, of the track rails to extend generally in the direction of the track. An indicating means is mounted on a carriage and includes two independently movable indicating elements. Each indicating element is coupled with a respective one of the chordal elements for moving the indicating elements in dependence on the chordal elements and a common mounting means is provided for both indicating elements for cooperatively moving one of the elements in relation to the other one.

In the preferred embodiment, the chordal elements are tensioned wires and the longer wire extends in a plane parallel to the track plane and farther spaced therefrom than the plane wherein the shorter wire extends. In this embodiment, the common mounting means may be a common pivot about which the indicating elements may swing and the common pivot may be spaced at any desired distance from the associated rail.

The above and other objects, advantages and features of the present invention will be more fully understood with reference to the following detailed description of a specific embodiment thereof, taken in conjunction with the accompanying drawing wherein

FIG. 1 schematically shows a top view of the preferred track aligning arrangement of this invention; and

FIG. 2 is a schematic front view of the indicating means of the arrangement.

Referring first to FIG. 1, there is schematically shown a track aligning machine 1 movable on and along the track rails 31, 31'. Since movable track aligning machines are well known, the operating mechanism of this machine is not illustrated, the transversely extending arrows indicating simply that the machine includes means for moving the track rails laterally of the track direction in either lateral direction.

In the illustrated embodiment, each track rail has associated therewith a respective aligning arrangement according

2

to the invention, the arrangement associated with one rail being an exact replica of the arrangement associated with the other rail and the duplicated parts being designated by the same reference numerals bearing a prime.

5 The track aligning arrangement operates with two chordal reference elements, one of which is longer than the other. However, to make the arrangement readily reversible so that it may be moved for operation in either direction, the preferred arrangement includes two like short chordal reference elements for a purpose to be explained hereinafter. Also, as illustrated, the preferred chordal reference elements are tensioned wires.

As shown in FIG. 1, a pair of like chordal reference elements 2 and 2' is associated with each of the track

15 rails 31 and 31' and the reference elements extend generally in the direction of the track in either direction of track aligning machine 1. One of the end points 3, 3' of the elements 2, 2' is mounted on the track aligning machine while their other end points 4, 4' and 5, 5' are mounted on a pair of support carriages 14 and 14' which are arranged on either side of the track aligning machine. Thus, each of the tensioned wire lengths 2, 2' stretches from one end point 3, respectively 3', to their respective end points 4, 4' and 5, 5' on the support carriages 14 and 14'. In the illustrated embodiment, each pair of chordal elements 2, 2' is constituted by a tensioned length of wire trained, respectively, over pairs of rollers 3, 3'. The two ends of each wire are attached at points 4, 4' and 5, 5', respectively, to cross bars mounted on carriages 14, 14'.

20 30 An additional pair of carriages 6 and 8 are movable along the track and a respective one of the latter carriages is arranged between the track aligning machine and a respective support carriage 14, 14'. The carriages 6, 8 carry the indicating means of the present invention and the alignment indicating positions on the track rails are indicated by 7, 7' and 9, 9'.

25 The longer chordal reference element 10 and 10' is shown to be mounted with its end points 12, 12' and 16, 16' on another pair of support carriages 11 and 15. As can be seen from FIG. 1, the support carriages 14, 14' are arranged between the support carriages 11, 15 and the track aligning machine 1, the longer chordal reference element 10, 10' also extending generally in the direction of the track in either direction of the track aligning machine.

30 35 40 45 Means is provided for adjusting the distance of the support carriages 11 and 15 in relation to track aligning machine 1 whereby one of the like chordal reference elements 2, 2' may be selectively positioned at least approximately centrally between the end points 12, 16 or 12', 16' of the longer chordal reference element. The illustrated distance adjusting means are adjustable spacing rods 13 for instance telescopic rods, coupling the support carriages 11 and 15 to the track aligning arrangement. Thus, the respective end points of the longer chordal reference element are so 50 55 60 65 movable in relation to the track aligning machine that either one or the other of the like chordal elements 2 may be positioned centrally of the longer chordal element 10, depending on the direction of operation of the track aligning arrangement along the track. As indicated by the arrow at the right of FIG. 1, the arrangement is illustrated advancing toward the right. In this operating direction, the indicating position for the track alignment is at 7. If the direction were reversed, support carriage 15 would be moved outwardly away from track aligning machine 1 and carriage 11 would be correspondingly moved toward the track aligning machine. This would make the indicating position 9 operative.

70 Thus, either indicating position 7 or 9 is at least approximately centrally between the end points of the longer chordal element. Positioned on either side of the indicating position are two pairs of supporting carriages 1, 14 and 11, 15 for mounting the end points 3, 4 and 12, 16 of

the shorter and longer chordal elements, respectively, the respective distances of the support carriages of each pair from the indicating position being at least approximately the same.

The indicating means mounted on carriages 6 and 8 at respective indicating positions 7 and 9 is shown in FIG. 2. As illustrated a pair of like indicating means is associated with rails 31 and 31', like parts of the indicating means at positions 7' and 9' being designated by like reference numerals but being primed.

The indicating means includes two independently movable indicating elements 20 and 21. A common mounting means, shown as pivot 24, is provided for both indicating elements for co-operatively moving the indicating elements about the common mounting means, i.e. by pivoting one in relation to the other element.

Means is provided for changing the distance of the common pivot 24 from the associated rail 31 at will, the illustrated distance adjusting means including rods 22 each carrying one of the pivots 24, 24' and spacing discs 23 which are pressed against the rails by a coil spring 22a mounted on the rods between the spacing discs. Each disc engages a respective one of the rails and thus maintains the pivots at a set distance from the rails, the distance being determined by the setting of the spacing discs on rods 22.

Means is also provided for coupling each indicating element with a respective one of the chordal reference elements for moving the indicating elements in dependence on the chordal elements to which they are respectively coupled about the common pivot 24. In the illustrated embodiment, the coupling means includes an elongated slot in each of the indicating elements 20 and 21, the slot in element 21 being shown to be engaged by the longer tensioned wire reference element 10 while the slot in element 20 is engaged by the shorter tensioned wire reference element 2. As the indicating means is moved relative to the chordal reference elements, the tensioned wires will automatically swing the respective indicating elements about their common pivot relative to one another.

As shown, the indicating means also includes an electrical indicating circuit which comprises two electrical contacts 25 and 26 mounted on the one indicating element 21 while the other indicating element 20 is designed as a contactor arranged to be moved into contact with a respective one of the contacts 25, 26. The contactor is thus moved by the shorter chordal element 2 and is pivoted thereby in relation to the contacts 25, 26 arranged on the indicating element 21.

Contact of the contactor with one of the contacts 25, 26 closes the indicating circuit and thus actuates suitable signal means in the circuit for indicating in which lateral direction the associated rail is to be moved for the desired alignment. These signal means may be, for instance, different colored electric bulbs 27 and 28 which receive power from separate power sources 29 and 30 when the circuit is closed. If the contactor element 20 is pivoted into the neutral position between the contacts 25, 26, the circuit is opened and no power is supplied to the signal means 27 or 28. This indicates that no alignment of the track is needed at this particular indicating position.

It is, of course, fully within the skill of the art to connect the indicating circuit to servo motor means, such as hydraulic motors or eccentric vibrators, which engages a respective rail and laterally moves the same toward the right or left in response to the signal from the indicating circuit. In this manner, the electric indicating circuit forming part of the track aligning arrangement of the present invention makes a fully automated alignment operation possible.

In a single aligning operation, only a single indicating means associated with one of the rails is required. However, to make the arrangement useful for aligning track curves turning left as well as right, a like indicating ar-

rangement is associated with each of the rails, the two arrangements being exact duplicates of one another.

As shown, it is preferred to have the shorter and longer chordal reference elements extend in different planes parallel to the track plane, the longer chordal element 10 extending in a plane farther spaced from the track plane than the plane wherein the shorter chordal element 2 extends.

Preferably, if the distance of the shorter wire 2 from pivot 24 is d , the distance of the longer wire 10 from the pivot is chosen to be n^2d , n being the ratio of lengths of the two wires. It is advantageous to make the longer chordal reference element 31.6 m. long and the shorter chordal element 10 m. long because the square of the ratio n ($31.6^2:10^2$) is about 10 so that the ordinate of the short chordal element is always a tenth of the ordinate of the long chordal element.

The track curve, which is to be aligned, has the correct curvature when the common pivot 24 of the two indicating elements 20, 21 is in alignment with the two chordal elements 2 and 10 in the plane perpendicular to the track axis. The distance of the pivots 24, 24' from the track rails 31, 31' is preferably so chosen that the pivot is in vertical alignment with the two chordal elements when the track runs straight. However, this is not an absolute requirement for the operability of the aligning arrangement.

The usefulness of making the arrangement readily operable in either direction of the track lies in the practical operating conditions which often require alignment of the track in both directions from a fixed point, such as bridges, cross paths and the like.

As will be appreciated, the entire arrangement may be readily removed from the track to permit through traffic during maintenance and alignment operations. All that is required is the removal of the coupling rods 13 and reeling of the longer tensioned wire 10 to move the outer carriages 11 and 16 toward the track aligning machine 1, the coupling rods may be telescoped into these bores as the outer support carriages are pulled toward the machine by winding the tensioned wire on spools or reels. All of the carriages may run up on auxiliary rails and the whole assembly may be hydraulically lifted and secured in position, whereupon the track aligning machine, with the carriages secured thereto, may be laterally moved from the track in any suitable and conventional manner.

While the invention has been specifically described and illustrated in connection with one preferred embodiment, it will be clearly understood that many modifications and variations may occur to the skilled in the art, particularly after benefiting from the present teaching, without departing from the spirit and scope of this invention as defined in the appended claims.

What is claimed is:

1. An arrangement for aligning track rails comprising, in combination:
  - (a) two chordal reference elements of unequal length associated with one of said rails and extending generally in the direction of the track;
  - (b) support means for mounting the end points of the chordal elements;
  - (c) means for moving the support means along the track;
  - (d) a carriage movable along the track and arranged between the end points of the two chordal reference elements;
  - (e) an indicating means mounted on said carriage, said indicating means including two independently movable indicating elements;
  - (f) means for coupling each of said indicating elements with a respective one of said chordal elements for moving said indicating elements in dependence on the chordal elements;
  - (g) a common pivot for said indicating elements about

which one of said indicating elements is pivotal in relation to the other; and
(h) means for changing the distance of the common pivot from the associated one of said rails.

2. The arrangement of claim 1, wherein said chordal reference elements are tensioned wires. 5

3. The arrangement of claim 1, wherein said indicating means is at least approximately centered between the end points of one of the chordal elements.

4. The arrangement of claim 1, wherein the two chordal reference elements extend in different planes parallel to the track plane. 10

5. The arrangement of claim 4, wherein the plane wherein the longer chordal element extends is farther spaced from the track plane than the plane wherein the 15 shorter chordal element extends.

6. The arrangement of claim 1, wherein said chordal reference elements are tensioned wires, and said coupling means includes a slot in each of said indicating elements, the slots being engaged by a respective one of said tensioned wires for pivoting the indicating elements about said pivot. 20

7. An arrangement for aligning track rails and movable along the track in either direction thereof for operation in either one of said directions, said arrangement comprising, in combination: 25

(a) a track aligning machine movable on and along said track;

(b) a pair of like chordal reference elements associated with one of said rails and extending generally in the direction of the track in either direction of the track aligning machine, one of the end points of said chordal reference elements being mounted on said track aligning machine; 30

(c) a pair of support carriages arranged on either side of the track aligning machine on the track for mounting the other end points of the like chordal reference elements; 35

(d) a third and longer chordal reference element associated with said one rail and also extending generally in the direction of the track in either direction of the track aligning machine; 40

(e) another pair of support carriages for mounting the end points of said longer chordal reference element, the support carriages of said first-named pair being 45 arranged between the support carriages of said other pair and said track aligning machine;

(f) means for moving said support carriages along the track; 50

(g) an additional pair of carriages movable along the track and a respective one of said latter carriages being arranged between the track aligning machine and a respective one of the support carriages of the first-named pair;

(h) means for adjusting the distance of the support carriages of said other pair in relation to the track aligning machine whereby one of said like chordal 55

reference elements may be selectively positioned at least approximately centrally between the end points of the longer chordal reference element;

(i) an indicating means mounted on each of the carriages of said additional pair, said indicating means including two independently movable indicating elements;

(j) means for coupling one of said indicating elements of each indicating means with the longer chordal reference element and the other one of said indicating elements of each indicating means with a respective one of said like chordal reference elements for moving said indicating elements in dependence on the chordal element to which they are coupled; and (k) a common mounting means for the indicating elements of each of said indicating means for cooperatively moving one of said indicating elements in relation to the other.

8. An arrangement for aligning track rails comprising, in combination:

(a) two chordal reference elements of unequal length associated with one of said rails and extending generally in the direction of the track;

(b) support means for mounting the end points of the chordal elements;

(c) means for moving the support means along the track;

(d) a carriage movable along the track and arranged between the end points of the two chordal reference elements;

(e) an indicating means mounted on said carriage, said indicating means including two independently movable indicating elements;

(f) means for coupling each of said indicating elements with a respective one of said chordal elements for moving said indicating elements in dependence on the chordal elements; and

(g) a common mounting means for said indicating elements for cooperatively moving one of said indicating elements in relation to the other; and

(h) an electrical indicating circuit including two electrical contacts mounted on one of said indicating elements, the other one of said indicating elements being a contactor arranged to be moved into contact with a respective one of said contacts.

9. The arrangement of claim 8, further comprising

(i) signal means actuatable upon closing of the indicating circuit by said contact and designed to indicate in which lateral direction the associated rail is to be aligned.
